UNITED STATES PATENT OFFICE

LUDWIK KAMINSKI, OF NEW YORK, N. Y., ASSIGNOR TO CORNELL-UNITY, INC., OF NEW YORK, N. Y., A CORPORATION OF NEW YORK

DESIGN FOR A SHOE OR SIMILAR ARTICLE

Application filed May 16, 1933. Serial No. 48,132. Term of patent 3½ years.

To all whom it may concern:

Be it known that I, LUDWIK KAMINSKI, a citizen of the Republic of Poland, and a resident of the borough of Manhattan, in the city, county, and State of New York, have invented a new, original, and ornamental Design for a Shoe or Similar Article, of which the following is a specification, reference being had to the accompanying drawing forming a part thereof.

Fig. 2 is a top plan view thereof; and

Fig. 3 is a cross-section on line 3—3 of Fig. 1.

I claim:

The ornamental design for a shoe or similar article substantially as shown.

LUDWIK KAMINSKI.
